UNITED STATES PATENT OFFICE.

ALEXANDER M. ALEXANDER, OF BEVERLY, MASSACHUSETTS, ASSIGNOR TO UNITED SHOE MACHINERY COMPANY, OF PATERSON, NEW JERSEY, A CORPORATION OF NEW JERSEY.

INSOLE-REINFORCING MACHINE.

1,143,016.

Specification of Letters Patent. Patented June 15, 1915.

Application filed October 21, 1914. Serial No. 867,761.

To all whom it may concern:

Be it known that I, ALEXANDER M. ALEXANDER, a citizen of the United States, residing at Beverly, in the county of Essex and 5 State of Massachusetts, have invented certain new and useful Improvements in Insole-Reinforcing Machines; and I do hereby declare the following to be a full, clear, and exact description of the invention, such as 10 will enable others skilled in the art to which it appertains to make and use the same.

This invention relates to machines for applying reinforcing fabric to lipped insoles and more particularly to devices in such machines for trimming the fabric to the contour of the insole.

From the time that reinforced insoles of the "Gem" type, wherein the fabric is beaded or crimped about the lip, were first 20 introduced, and until recently, it has been the practice to trim the fabric along a line coinciding with the edge of the insole. It has long been recognized that the raveled threads showing beyond the edge of the insole are undesirable as they render the sole 25 unsightly and detract from its selling qualities. Various experiments have been made to avoid the trouble with the result that it is now coming to be the general practice to 30 trim the fabric, particularly at the shank, along a line spaced from the edge of the insole, that is, the fabric is trimmed inside of the insole edge instead of at its edge.

The object of the present invention is 35 to provide novel means for trimming the fabric so as to prevent the fabric on reinforced insoles from being seen when viewing the insole from its grain, or unreinforced, side. In accordance with this object the invention contemplates the provision, in a machine of the character described, of a knife located above the feather and within its edge, in combination with 40 means beneath the fabric for supporting it so that it may be cleanly severed by the knife and for also preventing a slitting of the feather, which would weaken the insole. To the accomplishment of this object, the 45 invention comprises the features and combinations of parts hereinafter described and particularly defined in the appended claims.

The features of the invention will be best understood from a description of the preferred embodiment thereof illustrated in the 50 accompanying drawings, in which the in-

vention has been shown as applied to the insole reinforcing machine exemplified by Letters Patent of the United States to John B. Hadaway, No. 614,860, dated November 29, 1898.

In the drawings, Figure 1 is a side elevation of the machine; Fig. 2 is a detail illustrating the mounting of the fabric trimming knife, and the resultant effect on an insole; Fig. 3 is an underside view of the 65 knife and its coöperating plate; and Fig. 4 is an enlarged detail illustrating the manner in which the knife coöperates with a slotted plate to shear the fabric.

The tools for supporting, feeding and 70 forming the bead or crimp in the reinforcing fabric and applying it to the insole, that is, the work table 1 and its step-by-step feeding mechanism; the inside and outside forming tools 2 and 3 respectively and their 75 operating mechanisms; and the anvil or former 4, which also by its engagement with the lip performs the function of a gage to determine the position of the insole in the machine, may be, and preferably are, substantially the same as the corresponding parts in the Letters Patent to John B. Hadaway hereinafter referred to, to which patent reference may be had for a detailed description thereof.

Referring now to the novel fabric trimming mechanism forming the particular subject matter of the present invention, in the illustrated embodiment of the invention the knife operating mechanism of the Hadaway patent is retained, that is, the machine is provided with a horizontal rotary knife shaft 5 suitably journaled in the carriage 6 and driven by the engagement of a lug 7 on the rear end of the shaft, in a slot 8 95 formed in a drum 9 carried by a stud shaft 10 mounted to rotate in a bearing on a standard 11 supported on the main frame, and driven by a belt-pulley 12. The carriage 6, with its adjustments, is the same in 100 construction as the corresponding part in the Hadaway patent except that the arm 13 is not provided with a spring, a spring being unnecessary in the present construction, and the stop screws 14 engaging the arm 13 105 are used for a different purpose than heretofore, as will be hereinafter explained.

At the forward end of the shaft 5 there is mounted a disk knife 15. A horizontally arranged plate 16 is secured by set screws to 110

the under side of the forward bearing for the shaft 5 and projects forwardly to a position below the knife. During the operation of the machine the forward end of the 5 plate 16 enters between the feather of the insole S and the reinforcing fabric F, as shown in Fig. 2, and its end portion cooperates with the knife to secure a clean severance of the fabric and also holds the fabric 10 in a position which enables a severance without danger of the knife cutting into the feather. To this end a spring 17 coiled about the shaft 15 bearing at its forward end against the frame 6 and at its rear end 15 against a collar 18 fast in the shaft, being similar to the corresponding spring in the Letters Patent to John B. Hadaway hereinbefore referred to, operates to draw the knife toward the rear and hold its cutting 20 edge yieldingly against the end of the plate. Preferably, although not necessarily, the plate 16 is provided at its acting end with a transverse slot 19 in which the knife may rotate. The plate 16 is adjustably mounted 25 in the frame 6 to permit the proper setting-up adjustment between it and the knife to be made.

The mode of operation of the machine to attain the object of the invention will be apparent to those skilled in the art. An initial 30 adjustment of the screws 14, for the size or style of sole being operated on, places the knife the proper distance from the operative end of the anvil or former 4 so as to effect a 35 line of severance spaced from the edge of the insole. The width of the feather in welt insoles varies, the widest portion being at the shank and it is at the shank only where a trimming of the fabric within the edge of 40 the insole is most essential. It will, therefore, be apparent that the present method of trimming from the lip or rib of the insole as a gage, will prevent the fabric from being entirely removed from the feather along 45 its narrower portions while yet producing a severance inside the edge at the shank, as shown at the left of the insole S in Fig. 2. Having set the knife to its desired position the reinforcing operation is proceeded with 50 in the usual way. The various forming tools, as in the machine of the Hadaway patent, apply the fabric which is simultaneously trimmed by the knife. As is customary in machines of this type the upper 55 surface of the plate 16 will be oiled to prevent the sticky fabric from adhering thereto as the insole is fed through the machine.

The present invention provides a simple 60 and effective mode of gaining the desired object by means readily applicable to the present commercial machine for forming a bead or crimp in the reinforcing fabric and securing it in place, in the process of making what is known as the "Gem" insole.

65 The nature and scope of the invention

having been indicated and its preferred embodiment having been specifically described, what is claimed as new is:—

1. An insole machine of the character described, having, in combination, means for supporting and feeding the insole and for operating on the reinforcing fabric at its marginal position, a plate extending beneath the fabric and slightly over the margin of the feather, and a knife above the fabric 75 constructed to coöperate with the end portion of said plate to sever the fabric along a line spaced from the edge of the insole.

2. An insole machine of the character described, having, in combination, reinforcing 80 fabric applying tools, a trimming knife above the fabric and slightly within the edge of the insole, and means beneath the fabric constructed and arranged to hold the fabric clear from the feather while it is 85 being trimmed by the knife.

3. An insole machine of the character described, having, in combination, means for supporting and feeding the insole and for operating on the reinforcing fabric at its 90 marginal portion, a vertically arranged rotary disk knife above the feather and slightly within the edge of the insole whereby the fabric is severed along a line spaced from the edge of the insole, and means beneath the 95 fabric and coöperating with said disk knife to prevent slitting the feather as the fabric is trimmed.

4. An insole machine of the character described, having, in combination, means for 100 supporting and feeding the insole and for operating on the reinforcing fabric at its marginal portion, a tool engaging the insole lip to guide the insole and determine its position relative to said operating means, a 105 horizontal rotary shaft, a disk fabric-trimming knife on said shaft above the feather and fabric, and spaced from the operative end of said tool a distance less than the width of the feather at the shank of the 110 insole, and a plate below said knife and beneath the fabric to hold the fabric away from the surface of the feather while the fabric is being trimmed by the knife.

5. A machine for applying reinforcing 115 fabric to lipped insoles, having, in combination, means for forming a bead or crimp on the reinforcing fabric and securing it to the lip of the insole and the feather, a plate extending beneath the fabric provided with a 120 slot located above the feather, and a rotary disk knife constructed and arranged to operate within said slot and coöperate with the plate to sever the fabric.

6. A machine for applying reinforcing 125 fabric to lipped insoles, having, in combination, means for forming a bead or crimp on the reinforcing fabric and securing it to the lip of the insole and the feather, a plate below the fabric having its end within the 130

edge of the insole, and a knife above the fabric having its cutting edge overlapping the end of the plate whereby the plate and knife coöperate to shear the fabric along a line within the edge of the insole.

7. An insole machine, of the character described, having, in combination, means for applying reinforcing fabric to the lip and feather of the insole; means constructed and arranged to support and hold the marginal portion of the fabric clear from the feather; and means for trimming the fabric, while so supported and held, along a line spaced at such distance from the lip that when said marginal portion of the fabric is applied its edge lies within the edge of the insole.

8. An insole machine, of the character described, having, in combination, reinforcing fabric applying tools; means constructed and arranged to support and hold the marginal portion of the fabric clear from the feather of the insole; and means for trimming the fabric, while so supported and held, operating in a vertical plane so located relative to the edge of the insole that the trimmed edge, when applied by said tools, lies within the edge of the insole. 20 25
